PAINT-MILL OR MILL TO TAKE A FLUID.

1,129,142.

Specification of Letters Patent. Patented Feb. 23, 1915.

Application filed June 20, 1913. Serial No. 774,933.

To all whom it may concern:

Be it known that we, THOMAS TORRANCE, JOHN ROWLAND TORRANCE, and HUGH NASH TORRANCE, subjects of His Majesty the King 5 of England, residing at Bitton, Gloucestershire, England, have invented certain new and useful Improvements in Paint-Mills or Mills to Take a Fluid, of which the following is a specification.

10 This invention is for improvements in a paint mill or mills of a type suited or adapted to the grinding of fluids or mixtures which become fluid after grinding, particularly of the type or mill consisting of an upper per-
15 forate grinding organ which forms a receptacle for the fluid or like substance and the lower aspect of which forms a grinding surface: the other grinding surface being a rotating disk which bears against the grinding surface of the receptacle. In the use of this type of mill the ground material exudes all around the area of contact between the grinding surfaces and it is collected and brought into a stream by a scraper or scrap-
20 ers, or equivalent means bearing on the outside of the mill. Now such mills have hitherto been subject to serious disabilities and defects, disabilities and defects which tell pronouncedly when such a mill is used in
25 grinding extremely fine colors such as for example with a gelatinous solution as in preparing a pigment mixture for use in the process of photographic carbon printing. If in such a mill as is referred to above the
30 contact surfaces are arranged to fit closely at the margin or beyond the range of the leading grooves, the grinding will be slow, while a minute wear or gape at the extreme margin will so effect the mill as to render
35 the grinding inefficient as the flow through will then become relatively rapid. As a consequence of these two contrary adverse conditions much time has necessarily to be spent in maintaining the mill in good ad-
40 justment as regards closeness of contact at the margin and the exact positions at which the leading grooves shall terminate. Further after the desirable adjustment has been effected, a very slight amount of wear
45 or use disturbs this adjustment so that me-
chanical treatment or repair becomes re-
peatedly necessary.

By and in accordance with the present invention the rotating and usually lower mem-
50 ber of a paint mill or mill to take a fluid as

hereinbefore defined is given a supplement-
ary motion of nutation or wavering where-
by there is obtained a definite and positive
feeding or carrying in and out of the fluid
by adhesion to the nutating or wavering 60
surface; this adhesion carrying the fluid
outward in a semi-positive manner or by
adhesion and surface tension much in the
same way that a rope or band pump carries
a fluid. Thus, even with the closest approxi- 65
mation of the grinding surfaces there is se-
cured a relatively rapid passage through of
the fluid, and at the same time thorough
grinding.

A further advantage realized by the pres-
ent invention is that leading grooves may be
largely, partially, or even wholly dispensed
with: the tendency of coarse particles to es-
cape grinding being thus proportionately
reduced, and the efficiency of the mill for 75
fine grinding being thereby promoted.

The nutation or wavering of the lower
member of the paint mill as carried out by
appropriate mechanical devices which sys-
tematically change the direction of the suc-
cessive nutations will so distribute the wear 80
on the grinding organs that the operation
becomes analogous to the grinding of an
optical flat or an optical curve and the fig-
ure is preserved so that repairs are seldom 85
or never required.

An obvious, convenient, and preferred
method of giving the rotating and usually
lower member of a paint mill a movement of
distributed or symmetrical nutation is by 90
imparting thereto an orbital or planetary
motion so that instead of running in true
concentricity with its fellow stone it is dip-
ping in and out in a progressive manner.

The invention may be conveniently and 95
advantageously carried out as shown in the
accompanying drawings.

In the accompanying drawings:—Figure
1 is a central transverse sectional elevation
of a paint mill according to this invention 100
the section being taken on line $\alpha\alpha$ of Fig. 2.
Fig. 2 is a side elevation. Fig. 3 is a plan
view illustrating the scraper applied to the
periphery of the lower grinding or like
stone, and Fig. 4 is a plan view illustrating 105
the scraper applied to the surface of the
lower grinding or like stone. Fig. 5 is a
front elevation partly in section of a modi-
fied form of paint mill according to this
invention, and Fig. 6 a plan view thereof. 110

Figs. 7 and 8 illustrate in elevation and plan view respectively a detail of the paint mill according to Fig. 5 with the scrapers applied to the periphery of the lower grinding 5 or like stone. Fig. 9 is a sectional plan view taken on line α α of Fig. 7.

As illustrated by Figs. 1 to 4 of the drawings the mill comprises two superimposed disk grinding members of suitable material, 10 as stone, the upper disk 1 of which is stationary. Preferably the operating surfaces of these disks are spherical, the operative surface of the upper disk being concave while the operative surface of the lower disk 15 2 is convex, and this lower disk is adapted as depicted to be rotated about its own axis and at the same time as its rotates to be given an orbital or planetary motion thereby realizing a combined lateral and circular 20 grinding action with a progressive dipping in and out of the lower disk which definitely assures the material being led or carried from the feeding hopper to the grinding surfaces and thence to the scraper or 25 scrapers or equivalent and produces a cooling action by virtue of the surface of the lower disk being progressively exposed to the air.

The compound motion of the disk 2 may 30 conveniently and advantageously be realized by fixing the same to rotate with a shaft 3 which is mounted in a swivel bearing 4 which allows the disk 2 to be rocked about the center of revolution of the 35 spherical surface of the disk 2. The lower end of the shaft 3 is rotatably mounted in a bearing 5 secured to the bevel wheel 6, whereby when such bevel wheel is rotated, the shaft is rotated about the central axis 40 of the machine to thereby move the disk 2 in an orbital path over the disk 1. The bevel wheel 6 is rotatably mounted on the spindle 7 on the base of the machine and is geared with the bevel wheel 8 secured to the 45 shaft 9 on which are mounted loose and fast belt pulleys; rotation of the grinding member 2 about its own axis being effected by a gear wheel 10 rigidly secured to the shaft 3 and meshing with the stationary internally toothed gear 11.

In the above construction as the disk 2 has an orbital movement in relation to the upper disk 1 the scraper 12 (which removes the material operated upon from the periphery of the disk 2 and directs it into the chute 13) is adapted to have a corresponding movement so that it always remains in contact with the disk 2. According to one 55 convenient arrangement the scraper 12 is carried by a rod 14 which is adjustably secured to an arm 15 mounted upon an extension 16 of the bush 4^a. The scraper 12 is rotatably secured to the upper end of the rod 14 so that it may be adjusted in relation 60 to the disk 2 to be applied thereon with the

necessary pressure, this adjustment being conveniently effected by means of the screw pin 17 co-acting with the arm 18 secured to the upper end of the spindle. The said arm 18 is also mounted on the shaft 14 so 70 that when desired it may be loosened to thereby allow the scraper to rotate away from the disk 2 such as for the purpose of cleaning. An additional scraper is preferably also utilized to remove the material operated upon from the spherical surface of the disk 2 during the interval of time it projects from one side of the disk 1. According to the device illustrated a scraper 19 is secured to an arm 19^a mounted upon a pivot 20 stationarily mounted in relation to the disk 1. In some instances in addition to the scraper being pressed upon the spherical surface 2 by its own weight it may be pressed upon such surface by the additional 75 force of the spring. In order that this scraper shall not foul the sides of the disk 2 it is adapted to be automatically lifted after it has operated upon the projecting spherical surface of the disk 2 and is adapted to be dropped when the disk 2 again projects beyond the disk 1 at that side of the machine to which the scraper is fixed. This 80 may be effected by the rod 21 which is moved upward to raise the arm 19^a and to 85 retain such arm in its raised position until the disk 2, following its orbital path projects from the side aforesaid of the disk 1 when it is allowed to drop. To raise the arm a cam 22 mounted on the bevel wheel 6 co-acts with an arm 23 adjustably secured to the rod 21, such arm being returned and 90 retained in its lowered position by means of the spring 24.

In order that the disks 1 and 2 may be 95 adjusted for fine or coarse grinding or to take up wear, improved means are provided. According to such improved means the stationary disk is adapted to be axially moved, 100 means adjustably mounted in the machine frame being provided for forcing the stationary disk toward the co-acting disk and means being also provided for normally forcing the co-acting disk members apart. According to the form illustrated the hopper 25 has screwed engagement with the flange 26 the end of such feed hopper 27 engaging in a recess 28 of the disk member 1, so that by screwing the feed hopper 25 through the flange 26 by the handles 29 the 105 disk member 1 will be forced downward toward the disk 2, the side projections 30 engaging in guides formed by the arm 31 constraining the disk 1 to have an axial movement only. The disk member 1 is normally forced upward by means of springs 32 which at one end abut on the flange 26 and at the other end upon the nut 33 of the bolt 34 which is secured to the disk member 1, 110 and by this arrangement the disk member 1 115

100

105

110

115

120

125

130

normally abuts against the end 27 of the hopper so that when the hopper is screwed downward it moves against the force of springs 32 and when screwed upward such 5 springs 32 cause the disk member 1 also to move upward therewith.

The upper portion of the frame 31 carrying the disk member 1 and hopper 25 is adapted to be pivoted at 35 to the base of 10 the machine, so that the upper portion of the machine may be swung back, such as to admit of the grinding members being cleaned, the pin 35^a being removable to admit of said swinging movement.

15 A trough member 36 located below the disk 2 has the swivel bearing 4 secured thereto and is provided with a lubricator receptacle 37, and with an outer channel 38 for receiving the material operated upon 20 which may fall from the disk, an intermediate channel being provided for the purpose hereinafter set forth.

The grinding disks may be water cooled although in some machines water cooling 25 means may not be incorporated. According to a convenient manner of effecting this the disks 1 and 2 are secured to castings 39 and 40 respectively, which are provided with chambers 41 and 42 for receiving water.

30 The water enters the chamber 41 and passes therefrom to the pipe 43 from which it passes to the chamber 42. This chamber is provided with an outlet 43^a which delivers the water into a trough 44 the water running away from such trough through the pipe 45. In order to conduct the water from the pipe 43 to the chamber 42 a pipe 46 passes down the hopper and has a ball and socket connection with the member 47 passing 35 through the disk member 2 and has also a ball and socket connection with a receiving cup 48 secured to the hopper, the pipe 46 thus being allowed to move with the disk member 2. This pipe 46 also acts as a stirrer 40 for the paint contained in the hopper 25. In order to provide for the hopper being adjusted in the flange 26 the cup 48 is mounted upon flat springs 49 which by being flexed compensates for the movement of the hopper 45 and allows the cup 48 to be always maintained at the same distance from the disk member 2.

If desired the water cooling arrangement 50 may be modified so that the grinding disks or the like 1 and 2 may be heated such as by means of steam.

In the modified form of paint mill according to Figs. 5 to 9 of the drawings, the compound motion of the disk 2 is realized as 55 before described by fixing the same to rotate with the swiveled shaft 3. The ball swivel 50 has its bearing formed partly in the spur wheel 51 and partly in a cup shaped member 52. The ball 50 is provided with slots 60 53 into each of which a projection 54 secured

to the spur wheel 51 is adapted to engage so as to admit of the nutation or wavering of the shaft 3 and consequently also of the disk 2 and at the same time to permit rotary motion to be imparted to the said shaft by the 70 spur wheel in the manner hereinafter to be described. The lower end of the shaft 3 is rotatably and slidably mounted in a footstep bearing 55 eccentrically secured to the spur wheel 56. The amount of eccentricity 75 of the footstep bearing 55 in relation to the axis of the spur wheel 56 is preferably arranged variable, and to this end an appropriate arrangement, as depicted, consists of making connection of the footstep bearing 80 to the spur wheel 56 through the medium of a slotted member 55^a fast to the spur wheel 56; this member admitting in virtue of the fastening receiving slot 55^b of variation in throw being imparted to the disk 2 as the 85 exigencies of the grinding render expedient. The spur wheel 56 meshes with a pinion 57 secured to the shaft 58 of a bevel wheel 59 actuated by a bevel wheel 60 which has rotation imparted by a belt pulley 61. A 90 pinion 62 which meshes with the spur wheel 51 is fixedly mounted on the shaft 58 and the top end of this shaft extends into a container 63. Mixers or agitators 64 are fixed to the end of the shaft 58 in the container 95 63 and are adapted to rotate in the latter so as to thoroughly mix the liquid paint introduced into the container. From the latter the liquid paint passes through a spout 65 and a perforation 66 provided in the disk 100 casing 67 fitting into the frame casing 67^a of the machine and the disk 1, which casing supports the disk whence the paint is fed between the disks 1 and 2 and therebetween is subjected to grinding, whereafter the 105 liquid paint is removed from the disk 2 by scrapers in the manner to be hereinafter described and being thereby collected into a stream is conducted to a receiver by a spout 68 of a casing 69.

According to the scraper arrangement depicted the scrapers 70 and 71 which operate on the side and top respectively of the disk 2 are carried by the shaft 3 through the medium of a sleeve 72 loosely mounted on 110 the said shaft. The scraper 70 is supported by an arm 73 the one end of which is integral with the sleeve 72 while the other end thereof carries a sleeve 74 to which is secured a rod 75 supporting the scraper 70 in 115 scraping or collecting relationship with the sides of the disks 2. The scraper 71 is fixed to a rod 76 pivotally mounted to the casing 67 at 77 and the other end of the rod 76 has secured thereto a rod 78 loosely mounted 120 ball and socket joint fashion to an arm 79 integral with the sleeve 72.

In order to facilitate the rotation of the spur wheel 51 the same is mounted on an antifriction thrust bearing 80 which is sup- 125 130

ported by a plate 89 supported by uprights 81 and perforated to admit of the passage of the shaft 3.

As will now be seen a movement of nutation or wavering will be imparted to the disk 2 through the medium of the gearing 60, 59, 57, 56 and shaft 3 and at the same time the side scraper 70 will move in synchronism with the disk 2, and the scraper 71 10 will rise out of and fall into co-acting relationship with the grinding surface of the disk 2 in manner comparable to the action before described of the scraper 19. By the rotation of the gearing the shaft 58 and consequently also the mixers 64 in the container 63 and through the pinion 62 and spur wheel 51 the shaft 3 and with it the disk 2 will be caused to rotate; thus the disk 2 derives its compound movement of rotation and nutation or wavering.

In order that the disks 1 and 2 may be adjusted for fine or coarse grinding or take up wear the casing 67 carrying the disk 1 is supported on the pillars 81 supported from the base 82 which is suitably inclosed to form an oil bath for the gearing 56, 57, 59, and 60, and an adjustment of the contact surfaces of the disks is preferably realized from several points simultaneously. As illustrated this is effected by chain wheels 83 and screw nuts 83^a working on the pillars 81; these being operated simultaneously from a hand wheel 84 integral with one of the nuts 83^a, through the medium of a chain 85. On turning the hand wheel 84 the disk 2 is moved toward or away from the disk 1. Preferably springs 86 are interposed on the pillars 81 between the frame casing 67^a of the machine and the casing 69, which are carried by these pillars. The disks are secured in grinding position by hand screws 87 bearing partly on the frame casing 67^a and partly on the disk casing 67.

To permit cleaning or repairing or renewal of the disks the casing 67 is hingedly secured at 88 so that the said casing and with it the disk 1 can be swung clear.

The arrangement as described of the gearing 51 and 62 affords facilities for realizing a structure of great strength and rigidity and by a suitable provision of vertical walls 90, as depicted, to the plate 89 an oil bath for the said gearing 51 and 62 is obtainable.

While we have described the disk members 1 and 2 as being superimposed it will be obvious that they may be arranged on their sides, in which case the beveled gears 6 and 8 may be dispensed with and the bearing 5 may be secured directly to a belt driven 50 pulley.

It is to be understood that the invention is not limited to the herein-described preferred embodiments thereof as variations therefrom without departing from the principle of the invention and without sacrificing its chief

advantages may be made, the described embodiments being those which so far we have found to give the best results.

In its broader aspect the invention is equally applicable to dry grinding.

Having thus described our invention what we claim and desire to secure by Letters Patent of the United States of America is:—

1. A machine of the character described having co-operating disk grinding members 75 adapted to have relative rotary movement, means for producing such movement, and means comprising a shaft having positive and steady guidance by a ball and socket hinge action for imparting a nutation or 80 wavering movement to the revolving members whereby fluid is semi-positively carried into and out of the friction region and brought within the range of a collector and the wear on the grinding organs is distributed 85

2. A machine of the character described having a perforate grinding disk forming a receptacle for fluid mixture as defined, a revoluble co-acting grinding disk bearing 90 against the grinding surface of the perforate disk, means for rotating the revoluble disk, means for giving the rotating disk a supplementary motion of nutation or wavering whereby there is obtained a definite and positive feeding of the fluid by adhesion and a collector positively movable in synchronism with the nutating or wavering and rotating member to co-operate therewith substantially as described.

3. A machine of the character described having co-operating disk grinding members the operative surfaces whereof are part spherical, means for rotating one of said members about its own axis and simultaneously with such rotation moving the rotating member about an axis which is inclined to and which intersects the first mentioned axis at the center of sphericity, said means comprising a shaft for the rotating member 110 which shaft has positive and steady guidance by a ball and socket hinge action, substantially as described.

4. A machine of the character described having a perforate grinding disk formed 115 with a part spherical contact surface, a revoluble co-acting grinding disk the rotating motion whereof is supplemented by a nutation or wavering thereof, and means for effecting said compound motion comprising a rotating swiveled shaft having positive and steady guidance by a ball and socket hinge action with the center of said ball and socket corresponding to the center of sphericity substantially as described.

5. A machine of the character described having a nutating or wavering disk grinding member and a scraper combined to positively move in synchronism therewith substantially as described.

6. A machine of the character described having a nutating or wavering and rotating disk grinding member and means combined to positively move in synchronism therewith to bring the ground fluid mixture into a stream substantially as described.

7. A machine of the character described having co-operating disk grinding members adapted to have relative rotary movement, means for producing such movement, means for imparting a nutation or wavering movement to one of said members whereby fluid is semi-positively carried into and out of the friction region and brought within the range of a collector and the wear on the grinding organs is distributed, and stirring means connected to revolve simultaneously with the nutating member substantially as described.

8. A machine of the character described having a perforate grinding disk forming a receptacle for the fluid mixture as defined, a revoluble co-acting grinding disk bearing against the grinding surface of the perforate disk, means for rotating the revoluble disk, means for giving the rotating disk a supplementary motion of nutation or wavering whereby there is obtained a definite and positive feeding of the fluid by adhesion, a container for the fluid mounted on the frame of the machine, means operating simultaneously with the revoluble grinding disk for mixing or agitating the fluid in the container, means for discharging the fluid from the said container into the receptacle formed in the perforate disk, and a collector positively movable in synchronism with the nutating or wavering and rotating member to coöperate therewith substantially as described.

9. A machine of the character described having a perforate grinding disk forming a receptacle for the fluid mixture as defined, a revoluble coacting grinding disk bearing against the grinding surface of the perforate disk, means for rotating the revoluble disk, means for giving the rotating disk a supplementary motion of nutation or wavering whereby there is obtained a definite and positive feeding of the fluid by adhesion, a container for the fluid mounted on the frame of the machine, means for mixing or agitating the fluid in the container, rotation of the said mixing means being by means common thereto and to the revoluble disk, means for discharging the fluid from the said container into the receptacle formed in the perforate disk, and a collector positively movable in synchronism with the nutating or wavering and rotating member to coöperate therewith substantially as described.

10. A machine of the character described having a perforate grinding disk formed with a part spherical contact surface, a ro-

tating and nutating or wavering grinding disk co-acting therewith, means for effecting said compound motion of the last mentioned disk comprising a rotating swiveled shaft mounted in a swivel bearing corresponding to the center of sphericity and formed as a driving organ for rotating said shaft about its own axis and means for oscillating the said shaft about its swivel center, said oscillating means including an adjustable connection admitting of the amount of oscillation to be varied substantially as described.

11. A machine of the character described having a perforate grinding disk forming a receptacle for the fluid mixture as defined and formed with a part spherical contact surface, a rotating and nutating or wavering grinding disk co-acting therewith, means for effecting said compound motion of the last mentioned disk comprising a rotating swiveled shaft having the swivel center corresponding to the center of sphericity combined with means for rotating said shaft about its own axis and means for oscillating the same about said swivel center, said oscillating means including an adjustable connection admitting of the amount of oscillation to be varied, a container for the fluid mounted on the frame of the machine, means for mixing or agitating the fluid in the container, means for discharging the fluid from the said container into the receptacle formed in the perforate disk, and a collector positively movable in synchronism with the nutating or wavering and rotating member to coöperate therewith substantially as described.

12. A machine of the character described having a perforate grinding disk forming a receptacle for the fluid mixture as defined and formed with a part spherical contact surface, a rotating and nutating or wavering grinding disk co-acting therewith, means for effecting said compound motion of the last mentioned disk comprising a rotating swiveled shaft having the swivel center corresponding to the center of sphericity combined with means for rotating said shaft about its own axis and means for oscillating the same about said swivel center, said oscillating means including an adjustable connection admitting of the amount of oscillation to be varied, a container for the fluid mounted on the frame of the machine, means for mixing or agitating the fluid in the container, rotation of the said mixing means being by means common thereto and to the revoluble disk for effecting said compound motion of the rotating and nutating or wavering disk, means for discharging the fluid from the said container into the receptacle formed in the perforated disk, and a collector movable in synchronism with the nutating or wavering and rotating member

to coöperate therewith substantially as described.

13. A machine of the character described having a perforate grinding disk formed with a part spherical contact surface, a rotating and nutating or wavering grinding disk co-acting therewith, means for effecting said compound motion of the last mentioned disk comprising a rotating swiveled shaft 10 mounted in a swivel bearing corresponding to the center of the sphericity and formed as a driving organ for rotating said shaft about its own axis.

14. A machine of the character described 15 having a perforate grinding disk formed with a part spherical contact surface, a rotating and nutating or wavering grinding disk co-acting therewith, means for effecting said compound motion of the last mentioned 20 disk comprising a rotating swiveled shaft mounted in a swivel bearing corresponding to the center of sphericity and formed as a driving organ for rotating said shaft about its own axis and means for oscillating said

shaft about its swivel center, the driving 25 connection from said shaft about said swivel center to said driving organ permitting the shaft its supplementary motion of nutation.

15. A machine of the character described 30 having a nutating or wavering disk grinding member and a scraper combined to automatically move out of and into co-acting relationship therewith substantially as described.

16. A machine of the character described 35 having a nutating or wavering disk grinding member and collecting means combined to automatically move out of and into co-acting relationship therewith substantially as described.

In testimony whereof we affix our signatures in presence of two witnesses.
